UNITED STATES PATENT OFFICE.

CHARLES W. MITCHELL, OF BROOKLYN, NEW YORK.

DESIGN FOR A BOX-STRAP.

No. 38,039.

Specification for Design.

Patented May 29, 1906.

Application filed March 21, 1906. Serial No. 307,284. Term of patent 14 years.

To all whom it may concern:

Be it known that I, CHARLES W. MITCHELL, a citizen of the United States, residing at No. 1066 Bergen street, borough of Brooklyn, city and State of New York, have invented a new, original, and ornamental Design for Box-Straps, of which the following is a specification, reference being had to the accompanying drawing, forming a part hereof.

The figure is a plan view of a box-strap, showing my new design.

I claim—

The ornamental design for a box-strap as shown herein.

CHARLES W. MITCHELL.
